UNITED STATES PATENT OFFICE.

JAMES R. PRATT, OF DENISON, TEXAS.

CAN-COVER.

No. 905,362.

Specification of Letters Patent.

Patented Dec. 1, 1908.

Application filed May 9, 1907. Serial No. 372,781.

To all whom it may concern:

Be it known that I, JAMES R. PRATT, citizen of the United States, residing at Denison, in the county of Grayson and State of Texas, have invented certain new and useful Improvements in Can-Covers, of which the following is a specification.

My invention relates to containers for liquids and refers more especially to vessels constructed of metal and provided with screw or slip caps for stopping the filling orifice.

The chief objects of my invention are to provide a can closure that can be readily applied to the opening and removed therefrom, such closure having retaining means for preventing its displacement or loss; and to furnish a connecting means adapted to secure the cap or stopper to the main body of the vessel and at the same time permit a sufficiently free movement of the cover to prevent interference with the insertion of a funnel or filling spout within the opening when said cover is removed.

Further objects of my improved can closure are to produce attaching mechanism of such design as will permit the latter to be placed entirely within the interior of the cap, thus preventing any danger of injury to the attachment from contact with other articles and to furnish a device for the purpose set forth that will be simple in construction, efficient in its operation, economical to manufacture and readily applicable to a wide variety of containers such as cans, bottles, oil cups, spouts, etc.

I accomplish the above results by the employment of the device illustrated in the accompanying drawing which forms a part of this specification and in which:

Figure 1 is a sectional view of a can top, showing a retaining device located entirely inside the cap; Figs. 2 and 3 show modifications of the attachment illustrated in Fig. 1 which permit the cap to be swung away from the nipple so as to leave the orifice unobstructed; Fig. 4 is a sectional view of an oil cup having a slip cup to which a modified form of connection is applied, and Fig. 5 is a perspective view of the looped stem shown in Fig. 3.

Referring to the drawing in detail, the numeral 7 indicates the top of a can or nipple having threads formed therein. A cap 8 of the usual construction and furnished with a sealing disk 9 has threads 10 adapted

to engage the threads of said nipple and is furnished with a lug 11^a fixed in the center of the top of the cover. To this lug is pivotally attached a connecting member 12 bent at a right angle at the point 13 to form a vertical portion 14 which passes freely through holes in the flanges 15^a of a bracket 16^a secured to the inside of the can 6. After assembling the parts the lower free extremity 15 of the vertical arm 14 is bent into an eye or formed with a simple angle 17 to prevent its becoming disengaged from the bracket flanges.

It will be seen that the device is entirely concealed in the interior of the nipple 7 when the cover or cap 8 is in engagement therewith. The vertical portion 14 is made of sufficient length in all the forms shown to allow the cap to be elevated high enough to permit it to clear the nipple after which it can be swung upon the centers of motion sufficiently to uncover the aperture. The dotted lines show the position of the closure 8 which has been swung upon its center and is supported upon the margin of the nipple where it is in a convenient position to be quickly replaced upon its seat and is sufficiently out of the way to allow the introduction of a funnel or tube into the orifice.

It will be readily understood that the connecting member has a pivotal connection with the cover center for the two fold purpose of permitting the necessary rotary motion to be given to the said cover to engage and disengage it from its threaded seat upon the nipple.

In the modified form it may sometimes be considered desirable to remove the cap so as to be entirely displaced from the nipple and thus avoid any interference with a free opening. For this purpose I have designed the modifications illustrated in Figs. 2 and 3. In the former case the lug 11^a is replaced by an L-shaped rod or stem 18 projecting downward from the under surface of the cap 8, the upright member 14 of the connecting link engaging a modified form of bracket 19 which has a single flange, the lower end of the said upright passing freely through a hole 20 formed in the covering plate 21 of the body of the can, which is constructed to encroach upon the opening of the nipple, an orifice 22 being formed for the passage of the liquid contents of the can. In the case thus illustrated the cap may be swung away from the nipple after being un-

screwed therefrom, and can then be tilted upon the stem 18 as shown by the dotted position leaving the filling aperture unobstructed.

5 The modification shown in Fig. 3 permits the placing of the cap in practically the same relative position as in Fig. 2. The stem 18^a secured to the cap is made straight and the opening in the arm 12 through 10 which it passes is bent upon itself to form a slot 12^a as shown in Fig. 5 to permit the cap to be removed a greater distance from the nipple than would be possible were the opening in said arm contracted to a round 15 hole for the passage of the stem as in the other cases shown. A further advantage in this form lies in the fact that the vertical member 14 is shortened so that it does not extend below the nipple and this form of 20 connection can thus be used whether the top of the can body does or does not encroach upon the opening of the nipple skirt, since it needs only the single point of support 19.

In all the modifications hereinbefore described 25 the caps shown therewith have been provided with screw connection with the thimble or nipple of the can. In Fig. 4 is illustrated an adaptation of the connecting device for use with a slip cap 23 which engages 30 the external surface of an oil cup 24, the stem 25 being located eccentrically in the top of the cap and extending interiorly thereto, being permanently attached to the cup by a clip 26 which permits free play to 35 said stem, the latter being of sufficient length to allow the cover or cap to be slipped free from its seat, when it can be rotated to the position shown in dotted lines.

While I have shown my improved can 40 closure adapted to certain forms of nipples and applied to the filling apertures it is evident that the device is equally applicable to containers of different design, and the discharge orifices as well, without departing 45 from the spirit and scope of the invention and I do not wish, therefore, to be limited in its application, nor to the precise details of construction and application set forth.

Having thus described my invention what 50 I claim as new is:—

1. In combination with a container having a suitable neck, a closure, consisting of

a cap adapted to fit said neck, a perforated guide secured to the inner surface of said neck, a bent arm pivotally connected with 55 the inner surface of said cap, and having a pivotal and slidable connection with said guide.

2. In combination with a container having a threaded extension, a cap adapted to 60 engage said extension, a bent arm arranged within said extension, and pivotally engaging the center of said cap, a guide secured within said container and having alined 65 openings therein, and means connecting said arm and guide said means adapted to permit the cap to be turned on its vertical axis, to be raised and lowered relative to said container and to be swung toward and away from said extension, substantially as set 70 forth.

3. In combination with a container having an extension with an opening therein, a cap for said extension, and means attaching said cap to said extension said means 75 consisting of a bearing arranged within said container, a rod slidably mounted in said bearing and having a stop thereon and means 80 pivotally and slidably connecting said cap with said rod.

4. A device for securing a screw cap to a container, consisting of a bearing piece secured to said container, an arm pivotally mounted in said bearing and having an elongated eye formed therein, and means 85 connecting said eye with the top of the cap, said means adapted to limit the vertical movement of the cap relative to the container.

5. In means for securing a screw-cap to a 90 container, a rod secured to the cap and depending therefrom within the container, means on said rod for limiting the vertical movement of said cap relative to the container, and means connecting said rod with 95 said container, and adapted to permit the rotation of said cap on said container.

In testimony whereof I affix my signature in the presence of two witnesses.

JAMES R. PRATT.
